TIME CONTROLLED LINKAGE ACTUATING
MECHANISM

Ralph A. Barrett, Cleveland, Ohio, assignor to
The Apex Electrical Manufacturing Company,
Cleveland, Ohio, a corporation of Ohio

Application October 15, 1949, Serial No. 121,593

4 Claims. (Cl. 161—1)

1

This invention relates to mechanism for automatically actuating linkage after a predetermined time interval, and more particularly to a mechanism of this type including a spring operable clock wherein manual winding of the clock concurrently effects storage of energy for actuating the linkage at the termination of the time interval.

Linkage of the type contemplated herein may be employed for various purposes, such as disengaging the clutch of an agitator in a washing machine whereby the motion of the agitator may be automatically discontinued after a predetermined but variable time interval. In a well-known manner, agitator movement effects washing of articles disposed with water in a washing machine tub and for articles such as silks or rayons the washing action should be discontinued after an interval such as five minutes, whereas in washing linens the interval may be fifteen minutes. As another example, the mechanism may be used for automatically closing a valve controlling the gas supply to a stove after a predetermined interval. In other words, the gas would be ignited and the clock set for any desired interval and the flame would be automatically extinguished through cutting off the gas supply at the termination of the interval.

Spring operable clocks of the type contemplated herein have been previously used for controlling small electric switches through movement of a lever associated with the clock after a desired interval. Winding of the clock loads a cam member operably connected to the main spring and a detent prevents movement of the cam member and relieves the timing mechanism of the clock from undue load. At the expiration of the time interval the detent is moved by the timing mechanism, permitting the cam member to move by power from the main spring and this movement effects partial rotary movement of a lever disposed externally of the clock housing. Although this lever has sufficient power to move switch contacts against a light spring force, it does not have sufficient power to actuate linkage moving a clutch, gas control valve or the like. The present invention combines linkage of the type contemplated with a clock of this type in a manner causing an operator in winding the clock to exert additional force which will preload spring means associated with the linkage for actuating the linkage when the time interval has expired.

According to the invention, a conventional spring clock forms a unit with linkage adapted

2

to be connected to a clutch, valve or the like and the clock is provided with a dial type knob affixed to a shaft adapted to wind the main spring of the clock. The linkage and shaft are operably connected whereby the linkage is preloaded when the knob is rotated to set the clock for the desired time interval, and setting of the clock concurrently winds the same. A lever operable by the clock merely serves as a detent and is not required to transmit the load operating the linkage.

It is a primary object of the invention to provide mechanical linkage in association with a conventional spring operable clock and utilize the manual clock winding movement for providing additional energy to automatically actuate the linkage after a predetermined interval.

Another object of the invention is to provide means for automatically actuating a clutch, valve or the like after a predetermined interval and to utilize a portion of the energy required to rotate a dial knob for storing energy to actuate said means at the expiration of the interval.

Another object of the invention is to provide mechanism of the above type which is relatively simple and economical to manufacture.

Other objects of the invention and the invention itself will become increasingly apparent from a consideration of the following description and drawings, wherein:

30 Figure 1 is a fragmentary plan view of a mechanism embodying the invention, mounted in a washing machine, with parts being omitted and partially broken away for clearness of illustration;

35 Figure 2 is a front or left hand elevational view of the mechanism illustrated in Fig. 1;

Figure 3 is a side elevational view of the mechanism illustrated in Fig. 1;

40 Figure 4 is a rear elevational view of the clock and associated parts illustrated in Fig. 1; and

45 Figure 5 is a front view of a control knob I may employ.

Referring now to the drawings, I have indicated at 10 the frame or bottom portion of a washing machine which is generally cylindrical or rectangular in shape and encases the gear case, motor and other parts disposed beneath the tub. A cross brace 11 is fixed to opposite points in the frame and through a pair of bolts 12 supports a bracket 13. The bracket has a depending front flange 14 and has a timer shaft 15 extending from a clock 17 loosely projected through an opening in flange 14. The clock is 50 mounted in any suitable manner as by a pair of

screws 18 (one being shown) projected through the flange 14 and threaded into the front face of the clock housing. Shaft 16 has a suitable control knob 19 fixed thereto for rotating the shaft to wind the clock main spring, determine or set the time during which the clock will run, and preload spring means for actuating linkage to be described.

A lever 21 is mounted on the rear face of the clock housing which will be rotated in one direction when the clock or timer is set and will be automatically rotated in a reverse direction at the end of a predetermined time interval. The free end of the lever is bent to form an abutment indicated at 22. Through suitable mechanism the lever rotation during setting of the timer loads a light spring and the lever is held in rotated position by a detent to relieve the timing mechanism of any holding effort and at the end of the predetermined time interval the detent is automatically moved permitting the spring to move the lever in a reverse direction. The mechanism so far described is conventional and although the lever has sufficient power to operate switch contacts or the like it is not suitable for operating linkage to effect the purposes herein contemplated.

Fixed to the timer shaft 16 forwardly of the bracket flange 14 is a lever 23 which has one end of a generally L-shaped slide arm 24 pivoted thereto as indicated at 26. The opposite end of arm 24 has a pin 27 therein adapted to ride in a slot 28 formed in a link member 29. The right hand end of member 29 (Fig. 2) has a portion 31 extending laterally from its top edge which is pivotally connected by a pin 32 to one arm of a crank 33. Crank 33 is pivotally supported from bracket 13 by a bolt 34 and suitable washers and lock nuts. Integral with portion 31 of link member 29 is a horizontal arm 36.

Arm 36 at its free end has a laterally extending portion which terminates in a pair of upstanding and spaced ears 37 between which is mounted a rockable element 38 connected to ears 37 by a pin 39. A tension spring 40 has one end connected to bracket flange 14 and its opposite end connected to crank 33. A rod 41 has one end pivotally connected to crank 33 and its opposite end pivotally connected to a rock arm 42.

The operation of the parts so far described will now be explained. In the event the mechanism is adapted to disengage the agitator clutch of a washing machine the knob 19 is marked as indicated in Fig. 5 and the washing machine frame 10 will have an indexing button or the like 43 inserted therein. When the washing machine is not operating the knob 19 will be in the position of Fig. 5 with the "off" position aligned with button 43. Under these conditions the parts will be as illustrated in full lines, the free end of lever 21 being elevated as shown in Fig. 2 and spring 40 being substantially free of load. Knob 19 is rotated in a clockwise direction (Fig. 5) through a minimum of approximately 90° or to the eight minute indication. This movement causes lever 23 to force slide arm 24 through its maximum position of travel to the right (Fig. 2) carrying with it the link member 29 and the rockable element 38. At the same time the lever 21 rotates clockwise (Fig. 2) and the element 38 is so positioned that it moves slightly beyond the abutment 22 of lever 21 whereby lever 21 serves as a detent preventing reverse movement of link member 29 after the abutment 22 engages element 38. Due to its

connection with member 29, crank 33 is rotated and the spring 40 is tensioned or loaded. Movement of the crank through rod 41 rotates rock arm 42 to the dotted line position (Fig. 1) thereby engaging the clutch for driving the agitator. Clutches of the type contemplated are well known wherein partial rotary movement of an arm in one direction will engage the clutch and a reverse movement will disengage the same.

The rockable element 38 may be of inverted U form in cross section with its left hand end (Fig. 3) bent downwardly so it is adapted to rest on the top face of arm 36, the element being weighted relative to its support point to achieve this condition. Downward movement of lever 21 depresses the right hand portion of element 38 which has sliding contact therewith and after the element clears lever 21 the weight distribution causes the right hand portion to elevate and engage the lever abutment 22. To insure elevating movement I may provide a light spring which tends to keep the element in contact with the lever. It will be noted that although spring 40 may be relatively heavy the load on lever 21 is substantially a direct thrust and that little if any holding load is imposed on the clock mechanism. I preferably have the abutment 22 engage the depending sidewall of element 38 at a slight angle to prevent any tendency to bind when the lever starts to move in a reverse direction at the end of the timed interval.

It will be noted that the force for engaging the clutch is effected directly through the control knob or timer shaft and is not transmitted to the relatively delicate clock mechanism. Also, the preloading of spring 40 for disengaging the clutch is directly effected through the timer shaft. Although I have described the linkage as operating a washing machine clutch, it will be evident that it may be employed for operating various devices such as gas valves and the like. Although I have shown spring 40 as attached to crank 33 it will be evident that the same result could be obtained if it were connected to other parts of the linkage such as link member 29, rod 41, or rock arm 42.

If the time interval desired is such that slide arm 24 must be moved to its maximum travel position to the right (Fig. 2) the clockwise rotation of knob 19 is continued and pin 27 will ride in slot 28 to the left until the proper setting is reached. If the time interval desired is shorter than required to have lever 21 lock link member 29 in its maximum right hand position, knob 19 is rotated in a clockwise direction until this result is achieved and it is then rotated in a counter-clockwise direction to the proper setting such as three minutes. Clocks of the type described are designed so that if the knob is rotated beyond an automatic time zone the clock mechanism will be rendered inoperative to lift lever 21 and the agitator or the like will continue to operate until the knob is manually moved to the "off" position. Accordingly, in the present instance this would be effected if the knob were rotated to have the "hold" zone aligned with button 43. After the timer is set the clock rotates the timer shaft and knob in a reverse direction until the "off" position is reached and lever 21 is elevated permitting spring 40 to move link member 29 to the left (Fig. 2) thereby rocking arm 42 in a reverse direction to disengage the clutch or the like.

It will now be apparent that I have disclosed means whereby a conventional relatively light

clock adapted to be manually wound may be associated with linkage which the clock is not designed to operate in such a manner that the linkage is initially actuated by the same manual movement which winds the clock and at the same time preloads spring means adapted to automatically move the linkage in a reverse direction at the expiration of a predetermined time interval. The forces causing linkage movement are not transmitted through the clock mechanism and the only force absorbed by the clock is a substantially direct thrust on a lever which serves as a detent.

I wish it to be understood that I do not desire to be limited to the exact details of construction shown and described, for obvious modifications will occur to a person skilled in the art.

What I claim is:

1. The combination with a clock timer of the type having a shaft extending from the timer housing and a lever disposed externally of the housing whereby when the shaft is rotated from an "off" position the lever is moved in a given direction and after a predetermined interval dependent on the amount of shaft rotation the lever is automatically moved in a reverse direction, of linkage adapted to actuate a clutch or the like directly operable by the shaft without imposing any substantial load on the timer, said linkage comprising a movable link member, means operably connecting the shaft and link member whereby when the shaft is rotated from the "off" position the member will be moved in a given direction, means connected to the link member engageable by the lever when the shaft is rotated a predetermined amount from the "off" position to hold the link member against movement in a reverse direction, spring means operatively connected to the link member adapted to be loaded when the shaft is rotated from the "off" position, means adapted to operatively connect the link member with a clutch or the like, and the spring means being adapted to move the link member in said reverse direction when the lever is moved by the timer after a predetermined interval determined by the amount of shaft rotation from the "off" position.

2. The combination as described in claim 1 and wherein the means operatively connecting the shaft and link member comprise a lever fixed to the shaft, a slide arm having one end pivotally connected to the shaft lever and its opposite end slidable in a slot provided in the link member whereby at maximum travel of the shaft lever towards the link member the slide arm will force the link member to a position permitting the timer lever to lock the link member against reverse movement.

3. The combination as described in claim 1 and wherein the holding means for the link member comprises a rockable element mounted on the link member and movable therewith, the rockable element being biased to normally engage the timer lever at an intermediate point thereof, and the rockable element being movable towards an end of the timer lever concurrently with movement of said lever end whereby when the rockable element moves slightly beyond the lever it will be tilted to engage the lever end thereby holding the link member in its moved position.

25 4. The combination as described in claim 1 and wherein the means adapted to operatively connect the link member with a clutch or the like comprises a crank pivoted at a point spaced from the link member and having one end connected to the link member, a rock arm pivoted at a point spaced from the crank, a rod interconnecting the crank and rock arm, and spring means adapted to be tensioned when the crank moves in a given direction for effecting movement of the 30 crank in a reverse direction.
